UNITED STATES PATENT OFFICE.

DAVID F. GRAHAM, OF COUDERSPORT, PENNSYLVANIA, ASSIGNOR TO GRAHAM
ROLLER BEARING COMPANY, OF COUDERSPORT, PENNSYLVANIA.

DESIGN FOR A SOCKET-WRENCH.

57,775.

Specification for Design.

Patented May 3, 1921.

Application filed April 12, 1920. Serial No. 373,406. Term of patent 7 years.

To all whom it may concern:

Be it known that I, DAVID F. GRAHAM, a citizen of the United States, and resident of Coudersport, county of Potter, State of Pennsylvania, (whose post-office address is c/o Graham Roller Bearing Company, Coudersport, Pennsylvania), have invented a new, original, and ornamental Design for a Socket-Wrench, of which the following is a specification, reference being had to the

accompanying drawing, forming a part thereof, which is a side elevation of a socket-wrench showing my new design.

I claim:

The ornamental design for a socket wrench as shown.

DAVID F. GRAHAM.
